(57) **CLAIM**

The ornamental design for a pull tab for a slide fastener, as shown and described.

DESCRIPTION

FIG. 1 is a front view illustrating a pull tab for a slide fastener;
FIG. 2 is a bottom view of the pull tab;
FIG. 3 is a top view of the pull tab;
FIG. 4 is a left side view of the pull tab;
FIG. 5 is a right side view of the pull tab;
FIG. 6 is a section view of the pull tab taken along the line 6-6
of FIG. 1; and,
FIG. 7 is a front view showing the pull tab of FIG. 1 in
connection with a slide fastener slider body, the slide fastener
body being for illustrative purposes only and forms no part of
the claimed design.
